UNITED STATES PATENT OFFICE.

JOHN E. SKULSTAD, OF MADDOCK, NORTH DAKOTA.

CROSS-SPRING.

1,096,570.

Specification of Letters Patent. Patented May 12, 1914.

Application filed January 10, 1914. Serial No. 811,431.

To all whom it may concern:

Be it known that I, JOHN E. SKULSTAD, a citizen of the United States, residing at Maddock, in the county of Benson and State of North Dakota, have invented certain new and useful Improvements in Cross-Springs, of which the following is a specification, reference being had to the accompanying drawings.

10 This invention relates to certain improvements in cross springs and has relation more particularly to a device of this general character adapted to support a vehicle body, and the object of the invention is to provide a 15 device of this general character having novel and improved means whereby both vertical and horizontal jolt of the vehicle body is effectually compensated for and whereby the tension of the spring may be readily and conveniently adjusted as the dictates of practice 20 may require.

25 The invention consists in the details of construction and in the combination and arrangement of the several parts whereby certain important advantages are attained and the device is rendered simpler, less expensive and otherwise more convenient and advantageous for use, all as will be hereinafter more fully set forth.

30 The novel features of the invention will be carefully defined in the appended claims.

35 In order that my invention may be the better understood, I will now proceed to describe the same with reference to the accompanying drawings, wherein—

40 Figure 1 is a view in elevation of a cross spring constructed in accordance with my invention, the coacting portions of the axle being shown in fragment, a part being broken away to illustrate certain details of 45 my invention, as herein disclosed, while the remainder of the axle with its wheels and the adjacent portion of the vehicle body is indicated by dotted lines; Fig. 2 is a fragmentary top plan view of the device as illustrated in Fig. 1; Fig. 3 is a sectional view on the line 3—3 of Fig. 1. Fig. 4 is a view in elevation of a spring constructed in accordance with my invention particularly 50 adapted to be applied at the forward part of a vehicle; and Fig. 5 is a view in top plan with certain of the parts in section of the device as illustrated in Fig. 4.

55 As disclosed in the accompanying drawings, my improved cross spring comprises two duplicate sections extended in substan-

tially opposite directions, such sections being employed in order to facilitate production although it is thought to be obvious that the spring may be produced from integrally 60 connected sections. Each of the sections comprises the inner straight portion 3 adapted to be suitably connected with the similar portion of the second section, and such straight portions 2—3 serve as a base for the 65 weight to be carried and for that purpose are suitably secured to the under face of the vehicle body. Each section is provided with the extended portion 4 disposed on a sigmoidal curve and the outer extremity of the 70 extension 4 is adapted to be pivotally secured, as at 5, to a clamp member 6, such clamp member 6 being capable of adjustment longitudinally of the supporting axle 1 whereby it is thought to be obvious that 75 the tension of the spring or more particularly the sections thereof may be adjusted as required, it being obvious that inward movement of the clamp 6 results in a stiffening of the spring and vice versa. While 80 the outer extremities of the spring may be secured to the clamping member 6 in any member desired, I prefer that such extremities be bent to form a scroll or barrel 7 through which the retaining bolt or pintle 8 85 is adapted to pass, such bolt or pintle being mounted in the spaced ears 9 carried by the clamping members 6 and projecting upwardly from the shaft when the clamping members are in applied position. In having 90 each of the extensions sigmoidal in form and positioned entirely above the supporting axle 1, it will be observed that the downward curve of the extension serves to compensate for the vertical jolt of the vehicle, 95 while the upward curve serves to compensate for the horizontal jolt.

In Fig. 1, I disclose my spring as employed preferably at the rear of the vehicle but it is understood that it can be employed 100 with equal facility at the forward part of the vehicle, it only being necessary that in this latter instance the spring be in reverse position. As shown in these Figs. 4 and 5 the intermediate straight portion 10 is suitably secured to the fifth wheel 11 while the extremities of the sigmoidal extensions 12 are suitably secured to the brackets 14 depending from the vehicle body 15, herein indicated in section.

110 From the foregoing description, it is thought to be obvious that a cross spring

constructed in accordance with my invention is of a simple and inexpensive nature and is particularly well adapted for use by reason of the effective manner in which jolting is prevented and it will also be obvious from the foregoing description that my improved cross spring is capable of some change and modification without material departure from the principles and scope of the invention and for this reason I do not wish to be understood as limiting myself to the precise arrangement and formation of the several parts herein shown in carrying out my invention in practice.

15 I claim:

1. In combination with a vehicle body and a supporting axle therefor, of a cross spring interposed therebetween and positioned entirely above the supporting axle, such spring comprising a straight portion affording a base to receive the weight of the

body and having a sigmoidal extension, and means for attaching the extremity of the extension to the supporting axle.

2. In combination with a vehicle body and a supporting axle therefor, of a cross spring interposed therebetween and positioned entirely above the supporting axle, such spring comprising a straight portion affording a base to receive the weight of the body and 30 having a sigmoidal extension, and means adjustable longitudinally of the supporting axle for securing the extremity of the extension thereto, and whereby the tension of the extension may be regulated. 35

In testimony whereof I hereunto affix my signature in the presence of two witnesses.

JOHN E. SKULSTAD.

Witnesses:

I. J. HOUGH,
JOHN J. WOAGEN.
